UNITED STATES PATENT OFFICE.

JOHN A. SWANSON, OF WALTHAM, MASSACHUSETTS, AND ARNOLD A. POLLAK, OF WATERBURY, CONNECTICUT.

BANDAGE-DISPENSING DEVICE.

Application filed October 27, 1924. Serial No. 745,995.

This invention relates to dispensing apparatus and more particularly to a device for dispensing bandages, and the like.

One object of this invention is to provide a sanitary bandage dispensing machine in which it will be impossible for the unused bandage strip to be contaminated by contact with the fingers of the user.

A further object is to provide a bandage dispensing device provided with cups adapted to receive the common type of tightly wound bandage rolls, and having means for feeding strips of bandage therefrom without the necessity of rewinding said rolls upon reels or cores.

A further object is to provide a device of the above nature which will be simple in construction, inexpensive to manufacture, easy to manipulate, compact in size, and very efficient and durable in use.

With these and other objects in view there has been illustrated on the accompanying drawing one form in which the invention may be conveniently embodied in practice.

Fig. 1 represents a side view, partly in section and partly broken away, of the bandage dispensing machine.

Fig. 2 is a front view of the same, also shown partly in section and partly broken away.

Fig. 3 is a sectional plan view of the same taken on a plane just below the top cover of the casing.

Fig. 4 is a perspective view of one of the roll-holding cups.

In the ordinary use of a bandage roll, when a strip is being removed therefrom, it is difficult, if not impossible, to prevent the unused portion of the roll from becoming soiled and contaminated by the hands of the user.

By means of the present invention the above and other disadvantages have been avoided. This has been accomplished by providing a casing within which are located a plurality of metallic cups for holding said bandage rolls and through which the strips of bandage may be drawn whenever desired.

Referring now to the drawings in which like reference numerals denote corresponding parts throughout the several views, the numeral 10 indicates the base of the casing, said casing also having a front wall 11, a

rear wall 12, a top wall 13, and side walls 14 and 15.

The side walls are preferably made detachable from the casing and are adapted to be held in place at their front ends by cleats 16 and 17, and at their rear ends by rotary latches 18 and 19, said latches having hand knobs 20 and 21 located outside the casing. By means of this construction it will be possible for the operator by manipulating the knobs 20 and 21 to readily remove the side walls 14 and 15 of the casing whenever it is desired to recharge the device with fresh bandage rolls.

In order to loosely hold the bandage rolls within the casing where they will be protected from dust and other unsanitary sources, a series of horizontal cups 22, 23, 24, are provided, said cups being supported by spring clips 25. The clips 25 are rigidly mounted at equally spaced intervals upon an upright member 27 located near the rear of the casing. The member 27 has its lower end bent laterally to form a flange 28, said flange being secured to the base 10 of the casing in any suitable manner as by riveting. Each of the clips 25 is preferably provided on its inner face with a lug 29 adapted to register with an indentation 30 in the roll-holding cup, which is adapted to be interchangeably carried thereby.

In order to permit the strips of bandage or other material to be readily drawn out of the cups, each of the latter has a slot 31 extending from the open end nearly to the base thereof.

The slots 31 of the cups are preferably so arranged that the bandage strips may be fed out horizontally toward the front of the casing. Horizontal platens 32 are located between the cups and the front 11 of the casing and serve to support the bandage strips as they are being drawn out for use. Each of the platens 32 has a pair of side flanges 33 to guide the edges of the bandage strip and has a depending flange 34 at its forward end adapted to rest upon a knife member 35, the edge 36 of which is slightly below the plane of the platen. The platen 32 and the knife member 35 are adapted to be secured to the front of the casing in any suitable manner, as by rivets 37.

The bandage strips are adapted to be

drawn through slots 38 located in the front of the casing in alinement with the slots 31 and platen 32. The upper part of each of the slots 38 is bent outwardly to prevent the possibility of injury to the fingers of the user by the knife 36.

In order to feed the strips of bandage forward and out of the casing provision is made of a series of rollers 39 of soft rubber 10 or other resilient material, said rollers being adapted to press down upon said platen 32. The rollers 39 are carried upon shafts 40, said shafts being rotatably mounted in a pair of uprights 41 and 42 having flanges 15 43 and 44 respectively adapted to be riveted to the base 10 of the casing.

The left hand ends of the shafts 40, as viewed in Fig. 2 are provided with hand knobs 45, by means of which the roller 39 20 can be manipulated to feed forward the particular size of bandage desired.

In order to hold the bandage rolls properly positioned within the cups, covers 48 25 may be provided, said covers comprising flat discs having three upstanding lugs 49 adapted to embrace the sides of cups, and being readily removable therefrom whenever it is desired to replenish the device by inserting new rolls when the original rolls have been 30 exhausted.

The rollers 39 are prevented from accidental reverse movement by means of ratchets 46 and pawls 47, as clearly shown in Fig. 1.

While in the present illustrated embodiment of the invention, only one size of cup is disclosed, it will be understood that cups of different diameters may be employed within the same casing so as to accommodate bandage rolls of different dimensions.

One advantage of the present invention is that no cores or reels of any description are needed, permitting the common type of tightly wound bandage rolls to be used in their original forms.

While there has been disclosed in this specification one form in which the invention may be embodied, it is to be understood

that this form is shown for the purpose of illustration only, and that the invention is not to be limited to the specific disclosure 50 but may be modified and embodied in various other forms without departing from its spirit. In short, the invention includes all the modifications and embodiments coming within the scope of the following claims. 55

Having thus fully described the invention, what is claimed as new, and for which it is desired to secure Letters Patent, is:

1. In a bandage-dispensing device, a casing having a slot in one side, a holder in said casing, a removable hollow supporting container carried by said holder for loosely carrying a bandage roll, said container having a slot in alinement with the slot in said casing, a horizontal guiding platen located 60 between said supporting container and said casing, and a manually-operated roller pressing against said platen for propelling a strip of bandage along said platen and out through the slot in said casing. 70

2. In a bandage-dispensing device, a casing having a slot in one side, a vertical standard in said casing, a clip on said standard, a removable hollow supporting container carried by said clip, said container being adapted to loosely carry a bandage roll and having a slot in alinement with the slot in said casing, a horizontal guiding platen located between said supporting container and the wall of said casing, and a 80 manually-operated roller pressing against said platen, said roller having manipulating means extending outside of said casing, whereby a strip of bandage may be readily propelled in antiseptic condition along said 85 platen and out through the slot in said casing.

In testimony whereof, I have affixed my signature to this specification.

JOHN A. SWANSON.

In testimony whereof, I have affixed my signature to this specification.

ARNOLD A. POLLAK.
